UNITED STATES PATENT OFFICE

JOHN B. FLYNN, OF DETROIT, MICHIGAN, ASSIGNOR TO TERNSTEDT MANUFACTURING COMPANY, OF DETROIT, MICHIGAN, A CORPORATION OF MICHIGAN

METHOD OF FABRICATING STRIKERS

Application filed July 20, 1929. Serial No. 379,682.

This invention relates to a striker and method of fabricating same. It is the object of this invention to produce a striker for a refrigerator latch or the like that is strong, durable, and yet relatively simple in construction, and to set forth a method of fabricating such a striker that consists briefly of forming a bar of stock to a predetermined shape, removing or slicing a section from the bar, bifurcating an end of the section and then turning out the flanges to form a base for the striker.

In the drawings:

Fig. 1 is a perspective of a bar of stock having a predetermined cross-sectional shape.

Fig. 2 shows a section or portion which has been cut from the rolled stock bar.

Fig. 3 shows the section after one end has been bifurcated.

Fig. 4 shows the section after the flanges have been turned outwardly to form the base of the striker.

Fig. 5 is a side elevation of the striker.

Fig. 6 shows the striker after the base has been impressed with a suitable design and holes put therein for the reception of suitable attaching means.

Referring more particularly to the drawings wherein I have shown the method as applied to a specific type of striker, namely, a refrigerator latch striker, (but it is understood that this method is not limited to refrigerator latch strikers), I have shown a bar of rolled stock of any suitable metal or composition of metals, which may be generally be designated 1. The bar is rolled to a suitable cross-sectional shape, and,

since in this instance I have shown the method applied to a refrigerator latch striker, the cross-sectional shape of the rolled bar stock conforms to that of the refrigerator latch striker which is to be produced, the head portion of which may be designated 2 and the base portion 3.

After the stock has been rolled to the required predetermined cross-sectional shape, a section is sliced therefrom by any suitable operation such as sawing the bar along the

dotted line 4. This section may be designated 5.

After a section 5 has been removed from the rolled bar stock 1, the base portion of the section is bifurcated to form flange portions 7 and 8. The bifurcation of the base portion of the section may be achieved by means of a saw the withdrawal of which leaves the kerf 6. The flange portions 7 and 8 are then turned outwardly at substantially a right angle to the body portion 10 of the striker to the position shown in Fig. 4 to form the base of the striker. After the flanges 7 and 8 have been turned outwardly to form the base of the striker, suitable holes 9 may be punched or otherwise placed therein for receiving screws or any other suitable means for attaching the striker to a support. The base of the striker may also be impressed with any suitable ornamentation, such as that shown at 11.

From the above description, it is evident that I have disclosed a simple and efficient method for fabricating a latch striker that is strong and durable. Although in the above description of my method I have spoken only of utilizing rolled stock as the material out of which the striker is made, yet I wish it to be distinctly understood that I do not limit my method to any one particular type of stock. This method is equally well applicable to rolled, extruded, cast, or any other type of metal stock.

What I claim is:

1. The method of fabricating a striker for a refrigerator latch, or the like, which comprises forming a metallic bar into a predetermined shape, removing a section from such bar, removing a portion of said section to form an opening therein, and then turning the metal adjacent the opening to form a base for the striker.

2. The method of fabricating a striker for a refrigerator latch, or the like, which comprises forming a metallic bar into a predetermined shape, removing a section from such bar, bifurcating one end of the section, and then turning the bifurcated end outwardly to form a base for the striker.

3. The method of fabricating a striker for

5 a refrigerator latch, or the like, which comprises rolling a metallic bar into a predetermined cross-sectional shape to conform to a cross-section of the striker, removing a portion of the said section forming an opening therein, and then turning the metal adjacent the opening to form a base for the striker.

10 4. The method of fabricating a striker for a refrigerator latch, or the like, which comprises rolling a metallic bar into a predetermined cross-sectional shape to conform to the cross-sectional shape of the striker, removing a section from the said metallic bar, bifurcating an end of the section, and then turning the bifurcated end outwardly to form a base for the striker.

15 5. The method of fabricating a striker for a refrigerator latch, or the like, which comprises forming a metallic bar into a predetermined shape, removing a section from the said bar, sawing one end of the section and then turning the sawed end outwardly to form a base for the striker.

20 26 In testimony whereof I affix my signature.
JOHN B. FLYNN.
